DESIGN FOR A HANDBAG

Nathan Sloane and Max Sloane, Brooklyn, N. Y.

Application December 20, 1943, Serial No. 112,064

Term of patent 7 years

(Cl. D87—3)

To all whom it may concern:

Be it known that we, Nathan Sloane and Max Sloane, both citizens of the United States and residents of Brooklyn, in the county of Kings and State of New York, have invented a new, original, and ornamental Design for a Handbag, of which the following is a specification, reference being had to the accompanying drawing, forming a part thereof, and of which Figure 1 is a view in side elevation of a handbag in closed position showing our new design; Fig. 2 is a view in end elevation thereof; Fig. 3 is a view in side elevation showing the handbag in open position; Fig. 4 is a top view thereof.

Parts of the draw string are omitted in the several views.

The front and back of the handbag are identical.

The drawstrings are shown broken away in the several views to indicate indeterminate length.

The characteristic features of the design reside in the handbag disclosed having a carrying loop over the mouth of the bag and down the sides thereof as shown.

We claim:

The ornamental design for a handbag, substantially as shown and described.

NATHAN SLOANE.
MAX SLOANE.
